E. F. W. ALEXANDERSON

HIGH FREQUENCY SIGNALING SYSTEM

Filed April 10, 1922

Inventor:
Ernst F. W. Alexanderson
by *Alfred Davis*
His Attorney

UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

HIGH-FREQUENCY SIGNALING SYSTEM.

Application filed April 10, 1922. Serial No. 550,948.

To all whom it may concern:

Be it known that I, ERNST F. W. ALEXANDERSON, a citizen of the United States, residing at Schenectady, in the county of 5 Schenectady, State of New York, have invented certain new and useful Improvements in High-Frequency Signaling Systems, of which the following is a specification.

10 My present invention relates to high frequency signaling systems and more particularly to systems for producing interrupted continuous high frequency signaling currents. 15 The object of my invention is to provide a simple and efficient method and apparatus for producing interrupted continuous waves which will be particularly adapted for effective transmission of radio telegraphic 20 signals.

In carrying my invention into effect, I employ an electron discharge device of the well known three electrode type and arrange this in such a way that it will be 25 capable of producing oscillations of both audio and radio frequency. The apparatus is further adjusted and arranged in such a way that high frequency oscillations will be produced only during a portion of 30 each cycle of the audio frequency oscillations. By proper adjustment of the apparatus the high frequency oscillations produced may be made of substantially constant amplitude during the period when 35 they are being produced. High frequency oscillations produced in accordance with my invention because of the fact that they have a high decrement are more efficient for the transmission of signals than modulated high 40 frequency oscillations such as have been produced in ways heretofore proposed for producing modulated high frequency oscillations by waves of an electron discharge device.

45 The novel features which I believe to be characteristic of my invention are set forth with particularity in the appended claims, my invention itself however both as to its organization and method of operation will best be understood by reference to the following description taken in connection with

the accompanying drawing in which I have indicated diagrammatically one way of carrying my invention into effect.

I have indicated in the drawing an electron discharge device 1 of the usual three-electrode type. A supply circuit which includes a source of current 2 and inductances 3 and 4 is connected between the cathode 5 and anode 6. A high frequency oscillating circuit associated with the device 1 comprises an inductance 7 in circuit with the antenna 8 and capacities 9 and 10, this circuit being coupled by capacity 11 to the grid 12. The grid circuit also includes a low frequency oscillating circuit made up of capacity 13 and inductance 14, which is coupled to the inductance 4 in the supply circuit. The antenna 8 is grounded at 15 and the usual grid leak resistance 16 is connected between grid and cathode.

It will be apparent that with the arrangement described when so adjusted as to produce low frequency oscillations the potential of the grid varies at the audio frequency of the low frequency oscillations generated. If the device has suitable characteristics or the normal grid potential is adjusted to the proper value high frequency oscillations will be produced only 75 during a portion of each cycle of the low frequency oscillations. This portion may by suitable adjustment be made to be all of the positive half cycle, a part only of the positive half cycle, or all of the positive half 80 cycle and part of the negative. With the arrangement which I have described the point at which high frequency oscillations start may be made quite critical and the high frequency oscillations will quickly 85 build up to their maximum amplitude and continue at substantially constant amplitude during the entire period during which they are produced. A high frequency wave of this type is more efficient for the transmission of signals than the usual modulated wave which builds up slowly to maximum amplitude and dies down slowly.

I am aware that it has heretofore been proposed to produce modulated high frequency oscillations by means of a single electron discharge device. In none of the

systems which have been proposed for this purpose of which I am aware, however, have any means been provided for limiting the amplitude of the audio frequency oscillations in proportion to the amplitude of the radio frequency oscillations and there has been a general tendency in such systems for the audio frequency oscillations to rise in amplitude at the expense of the high frequency oscillations. In the system which I have described, however, it is apparent that the amplitude of the audio frequency oscillations will be limited by the amplitude of the radio frequency oscillations as the amplitude of the audio frequency oscillations is entirely dependent upon the amount of energy which is supplied to the tube and the greater part of this energy is converted into high frequency oscillations.

20 While I have shown and described the preferred embodiment of my invention it is apparent that many modifications in the circuit arrangement employed for carrying out my invention may be made without departing from the scope of my invention as set forth in the appended claims.

What I claim as new and desire to secure by Letters Patent of the United States, is:—

30 1. A system for producing interrupted continuous waves comprising an electron discharge device having a cathode, an anode, and a grid, a supply circuit connecting the cathode and anode and containing a source of current, a high frequency oscillating circuit in shunt to said supply circuit and coupled by capacity to a grid circuit, and a low frequency oscillating circuit associated with the grid circuit and inductively coupled to the supply circuit.

40 2. A system for producing interrupted continuous waves comprising an electron discharge device having a cathode, an anode and a grid, a supply circuit connecting the cathode and anode and containing a source of current, a radiating antenna, a high frequency oscillating circuit associated with the cathode and anode independent of said supply circuit, and with said antenna and coupled by capacity to a grid circuit and a low frequency oscillating circuit associated with the grid circuit and inductively coupled to the supply circuit.

50 3. The method of producing interrupted continuous waves by means of an electron discharge device which consists in generating low frequency continuous oscillations by means of said device and generating high frequency oscillations during the positive portions only of the individual cycles of the low frequency oscillations.

60 4. The method of producing interrupted continuous waves by means of an electron discharge device which consists in generating low frequency continuous oscillations by means of said device and generating high

frequency oscillations during a portion only of each individual cycle of the low frequency oscillations.

5. The method of producing interrupted continuous waves by means of an electron discharge device which consists in generating low frequency continuous oscillations by means of said device and generating high frequency oscillations during a portion only of each individual cycle of the low frequency oscillations, and maintaining the high frequency oscillations of substantially constant amplitude during the periods when they are generated.

6. The method of operating an electron discharge oscillation generator which consists in generating both high frequency and low frequency oscillations thereby and limiting the amplitude of the low frequency oscillations by the amplitude of the high frequency oscillations.

7. The method of operating an electron discharge oscillation generator which consists in generating high frequency oscillations thereby and generating low frequency oscillations thereby which are limited in amplitude by the amplitude of the high frequency oscillations.

8. A system for producing interrupted continuous waves comprising an electron discharge device having a cathode, an anode and a grid, a supply circuit connecting the cathode and anode and containing a source of current, a high frequency oscillating circuit in shunt to said supply circuit, a grid circuit, and a low frequency oscillating circuit associated with the grid circuit and inductively coupled to the supply circuit.

9. A system for producing interrupted continuous waves comprising an electron discharge device having a cathode, an anode and a grid, a supply circuit connecting the cathode and anode and containing a source of current, a radiating antenna, a high frequency oscillating circuit associated with the cathode and anode independent of said supply circuit, and with said antenna, a grid circuit and a low frequency oscillating circuit associated with the grid circuit and inductively coupled to the supply circuit.

10. A system for producing high frequency oscillations comprising an electron discharge device having a cathode, an anode and a grid, a supply circuit connecting the cathode and anode, a high frequency oscillating circuit associated with said device in such a way that high frequency oscillations will be produced therein, and a low frequency oscillating circuit associated with said supply circuit in such a way that low frequency oscillations will be produced therein of an amplitude proportional to the energy supplied to the device.

11. A system for producing high frequency oscillations comprising an electron

discharge device having a cathode, an anode and a grid, a supply circuit connecting the cathode and anode, a high frequency oscillating circuit associated with said device in 5 such a way that high frequency oscillations will be produced therein, and a low frequency oscillating circuit associated with said supply circuit in such a way that low

frequency oscillations will be produced therein of an amplitude proportional to the 10 amplitude of the high frequency oscillations produced.

In witness whereof, I have hereunto set my hand this 8th day of April, 1922.

ERNST F. W. ALEXANDERSON.
